UNITED STATES PATENT OFFICE.

JESSE E. McBRIDE, OF HIGHLAND PARK, MICHIGAN, ASSIGNOR TO PALMER-BEE COMPANY, OF DETROIT, MICHIGAN, A CORPORATION OF MICHIGAN.

APPARATUS FOR CONVEYING AUTOMOBILE-BODIES AND THE LIKE.

1,344,419.

Specification of Letters Patent. Patented June 22, 1920.

Application filed January 10, 1919. Serial No. 270,535.

To all whom it may concern:

Be it known that I, JESSE E. McBRIDE, a citizen of the United States of America, residing at Highland Park, in the 5 county of Wayne and State of Michigan, have invented certain new and useful Improvements in Apparatus for Conveying Automobile-Bodies and the like, of which the following is a specification, reference being had therein to the accompanying drawings.

The invention relates to the enameling of metallic bodies for automobiles and other heavy and bulky articles, and it is the object 15 of the invention to simplify and expedite the process, and to a large extent to eliminate the manual labor involved. To this end the invention consists in the novel construction of apparatus as hereinafter set 20 forth.

In the present state of the art such bodies are enameled by alternately coating and baking, several coats being necessary to produce the desired finish. The usual practice 25 is to manually apply the liquid coating, then to transfer the coated article to the oven where it remains stationary for a sufficient period of time to dry and harden the enamel. The article is then removed from the oven, 30 is re-coated and again transferred to the oven, these operations being repeated as often as necessary. Great care must be taken to protect the coated articles from dust and dirt while the coating is soft, and 35 also to avoid marring the surface by handling. The weight of the individual articles is such as to render the manual transferring difficult and laborious.

The present invention overcomes the difficulties by continuously carrying the articles during the entire process without interruption or transfer, and in alternately coating and baking at successive points in the path of advancement. The mechanism is 40 simplified and the power required for its propulsion is reduced by the use of several tunnel ovens arranged in a substantially straight line with intermediate spaces where the coating is performed. This permits of 45 using a straight line conveyer and avoids complication in the construction of the same.

In the drawings:

Figure 1 is a diagrammatic plan view;

Fig. 2 is a diagrammatic longitudinal section through my improved apparatus;

Fig. 3 is an enlarged view, similar to Fig. 2, showing the initial engagement of the work with the conveyer;

Fig. 4 is a similar view showing the means of disengaging the finished work from the 60 conveyer;

Fig. 5 is a cross-section;

Fig. 6 is a side elevation of one of the ovens;

Fig. 7 is an end elevation thereof.

65

A, A' and A² are ovens arranged in alignment with each other with a tail end space B and spaces B' and B² therebetween. These ovens may be formed of any suitable construction and may be heated by any suitable 70 means. I prefer, however, to heat the ovens electrically and to distribute the heat by radiation directly upon the work. To permit of the introduction and withdrawal of the work without excessive loss of heat, vestibules C and C' are arranged at opposite 75 ends, while the oven is in the form of a tunnel extending between these vestibules. The cross-section of the vestibule is but slightly greater than that of the work to be 80 introduced and is of suitable contour to reduce the clearance space to the minimum without danger of contact with or obstruction to the advancing work. D are flue connections for extracting the vapor-laden air 85 from the oven chambers at intervals throughout their length, and E are inlet flues for fresh air.

To advance the work through the series of ovens I have provided a single conveyer F 90 which extends in a straight line through the entire series and returns through a parallel path. This conveyer comprises a link chain G with cross shafts H at intervals and anti-friction roller bearings I upon these 95 shafts. The rolls travel upon tracks J which are arranged slightly below the ceiling of each oven and are spaced to provide clearance for hangers K which support the work. The return portion of the chain 100 passes above the ovens after first passing around sprockets L at each end.

The work is suspended from the hangers K which are provided with suitable hooks at their lower ends, suitable attachment means 105 being provided, such as the cross bars M having the central uprights M' with eyelets M² for engaging the hooks. The hangers K are permanently attached to the chain and pass around with the same through the 110

return orbit, but the attachment device M may be engaged at the tail end and removed at the head end.

To facilitate engagement the tail end of

5 the conveyer is slightly depressed to form an inclined portion N. This sufficiently lowers the hooks K' of the hangers K so that they may be inserted in the eyelets M² while the work is supported on the truck O.

- 10 This truck is used for transferring the work to the conveyer, and during the engagement of the hooks the truck may be manually moved forward until the rise in the conveyer will lift off the work therefrom. For 15 removing the work a conveyer P is arranged to extend beneath the articles, being provided with an inclined portion P' which will raise each article until strain is removed from the hooks, permitting of their 20 disengagement. The conveyer P preferably forms the assembly conveyer on which the work is supported, while various accessories are engaged therewith, and thus no transferring is required either during the 25 enameling process or the subsequent assembling.

In operation, the bodies, or other articles to be enameled, are successively brought to the tail end of the conveyer on the trucks O

- 30 and are engaged with the hooks K' as before described. When removed from the trucks the articles will be slowly advanced, first passing over the space B where the surface is coated with the liquid enamel, and then 35 passing into the oven A. The length of this oven is such that at the rate at which the conveyer is advancing the work will remain in the oven a sufficient time interval to dry or bake the first coat. As the work 40 emerges through the tunnel C' into the space B' it is again coated with the liquid enamel and then passes into the second oven A'. After passing it from the oven A' it is again coated in the space B² and 45 receives its final baking in the oven A². After emerging from this last oven the work is carried over the conveyer P and when the 50 rise in this conveyer relieves the stress upon the hangers the hooks may be disengaged from the eyelets, permitting the work to continue its movement beyond the conveyer F and during the subsequent assembling operation.

- The supporting of the work by suspension 55 means during the coating operations has a great advantage over supporting of the work by means arranged therebeneath. This is for the reason that anything below the coated article will be covered with drippings and will in time accumulate dirt, which is likely to injure the finished surface. On the other hand, the suspension means can be kept free from the liquid. I have also guarded against the dropping of 60 dirt from the conveyer upon the enameled 65

surface by guard flanges Q which are on the inside of the tracks J and rise above the level of the same.

What I claim as my invention is:

1. An apparatus, comprising a series of 70 ovens with intermediate spaces, a horizontal conveyer extending continuously through the series of ovens and intermediate spaces, and means for engaging the work with said conveyer at one end and removing it from 75 the opposite end.

2. An apparatus, comprising a series of ovens arranged in a straight line, said ovens being spaced from each other and provided with entrance and exit vestibules at their 80 opposite ends, a conveyer extending continuously through the series of ovens and intermediate spaces, and means for engaging the work with said conveyer at the tail end thereof and disengaging it from the 85 head end.

3. An apparatus, comprising a series of aligned tunnel ovens with intermediate spaces between said ovens, a conveyer extending continuously through the series of 90 ovens and intermediate spaces, a series of work suspension devices arranged along said conveyer, and means for engaging the work with said suspension devices at the tail end and removing it at the head end. 95

4. An apparatus, comprising a series of aligned tunnel ovens having intermediate spaces, a straight line conveyer passing through the series of ovens and intermediate spaces in a plane adjacent to the tops of the 100 ovens, and a series of depending work suspension devices on said conveyer.

5. An apparatus, comprising a series of aligned tunnel ovens with intermediate 105 spaces, a substantially straight line conveyer extending through said ovens and intermediate spaces in a plane adjacent to the tops of the ovens, work suspension devices depending from said conveyer, means for engaging the work with said suspension devices at the tail end of the conveyer, and 110 means for disengaging the work at the head end thereof.

6. An apparatus, comprising a series of aligned tunnel ovens with intermediate 115 spaces, a conveyer having a portion extending in a substantially straight line through the series of ovens and intermediate spaces in a plane adjacent to the tops of the ovens and having a return portion in a higher 120 plane, a series of work suspension devices on said conveyer, means at the tail end of the conveyer for supporting the work during engagement with said suspension devices and for lifting the work from its support during the advancement thereof, and means at the head end of the conveyer for lifting the work to facilitate the disengagement of the same from said suspension devices. 125

7. An apparatus, comprising a series of aligned tunnel ovens with intermediate spaces, a continuously operating work conveyer having a portion extending in a substantially straight line in a plane through and adjacent to the tops of said ovens and having a return portion outside of the ovens, a series of work suspension devices on said conveyer, means for engaging the work with said suspension devices at the tail end of the conveyer, and a conveyer beneath the work for receiving the same when disengaged from said suspension devices at the head end of said first-mentioned conveyer. 40
- 10 8. An apparatus, comprising a series of aligned tunnel ovens with intermediate spaces, a track extending in a plane through said ovens adjacent to the tops thereof, a series of work suspension devices supported on said track, and a conveyer to which said work suspension devices are attached, having a portion extending parallel to said track and a returning portion. 45
- 15 9. An apparatus, comprising a series of aligned tunnel ovens with intermediate spaces, a track extending in a horizontal plane through said ovens and intermediate spaces, work suspension trolleys for traveling on said track, an endless conveyer to which said trolleys are attached, having a portion adjacent to said track and a returning portion, means for depressing the tail end of the conveyer for engagement of the work with said work suspension trolleys, and a receiving conveyer extending beneath the head end of said first-mentioned conveyer in a plane beneath the work, said re- 50
- 55 ceiving conveyer having an inclined portion for lifting the work to disengage the same from said trolleys. 55
- 10 10. An apparatus, comprising a series of aligned tunnel ovens with intermediate spaces, an overhead conveyer extending through said ovens and intermediate spaces in a plane beneath the tops of the ovens, work suspension devices on said conveyer, and an underneath conveyer having a portion underlapping said overhead conveyer at the head end thereof to receive the work therefrom, said underneath conveyer being 60 extended to form a work assembling device. 60
11. An apparatus, comprising a series of ovens spaced from each other and provided with entrance and exit vestibules at their opposite ends, a conveyer extending continuously through the series of ovens and intermediate spaces and means for engaging the work with said conveyers at one end thereof and disengaging the work from said conveyer at the opposite end thereof. 65
12. An apparatus, comprising a series of aligned tunnel ovens with intermediate spaces, a track extending in a plane through said ovens adjacent to the tops thereof, a series of work suspension devices supported on said track, a conveyer to which said work suspension devices are attached having a portion extending parallel to said track and a returning portion, and a guard flange extending below and at the side of said track. 70

In testimony whereof I affix my signature.

JESSE E. McBRIDE.
